UNITED STATES PATENT OFFICE.

GEORGE BULLOCK, OF GRAND JUNCTION, COLORADO.

PENCIL-SHARPENER.

1,266,769.

Specification of Letters Patent. Patented May 21, 1918.

Application filed May 25, 1917. Serial No. 170,819.

To all whom it may concern:

Be it known that I, GEORGE BULLOCK, a citizen of the United States, residing at the city of Grand Junction, county of Mesa, 5 and State of Colorado, have invented a new and useful Pencil-Sharpener, of which the following is a specification.

This invention relates to pencil sharpeners.

10 An object of the invention is to provide a pencil sharpener that may be conveniently carried in the pocket and which is provided with means for retaining the pencil in connection therewith while in the pocket.

15 Another object of the invention is to provide an improved pencil sharpener including abrading surfaces between which the pencil is moved and by which the pencil is given the proper point, including a construction 20 by which the abrading action is stopped by contact of the pencil point against a part of the device when the pencil is properly sharpened.

25 Another object of the invention is to provide a pencil sharpener adapted to be carried in the pocket and to serve as a holder for pencils of different diameters.

30 Other objects will appear from the following description, in which I make reference to the accompanying drawing illustrating the preferred embodiment of the invention, in which drawings

35 Figure 1 is a perspective view of my improved pencil sharpener illustrating the method of holding the same and sharpening a pencil thereby.

Fig. 2 is a side elevation of the pencil sharpener with a pencil applied therein as a holder.

40 Fig. 3 is a view illustrating the blank from which the sharpener is formed.

Fig. 4 is a cross sectional view on the line 4—4 of Fig. 1.

45 Fig. 5 is a view illustrating the point produced on a pencil by use of my improved sharpener.

In the embodiment illustrated the device is composed of a single piece of sheet metal folded to provide two converging walls 1, 50 and two approximately parallel walls 2 which are in continuation of the walls 1 and between which the pencil is passed or inserted when it is to be sharpened. The fold 3 of the sheet metal is rounded so that the 55 point of the pencil being sharpened will contact with the inner surface of the fold

and thus stop or prevent further insertion of the pencil. The walls 1 are formed with numerous dentils or serrations 4 on their inner surface which are of proper size and 60 sharpened to cut or abrade the wood of the pencil until the lead point of the pencil prevents further cutting or abrasion by contact with the inner surface of the fold 3.

The walls 1 are also formed with a series 65 of dentils or serrations 5 which are adapted to work upon the lead and which are finer than the first named serrations 4. The serrations 5, however, are not formed upon the rounded inner wall of the fold 3, the latter 70 being smooth so that when the point of the pencil contacts therewith further insertion of the pencil between the abrading walls is prevented. By forming the sharpener in this way the lead of the pencil will be 75 tapered as illustrated at 6^a in Fig. 5, but will be left with a blunt or rounded point. Thus the pencil is given a proper point for writing, but the point is not sharply attenuated and will not easily break as in the case 80 of pencils sharpened by many of the sharpeners now in use.

The blank from which the device is formed is illustrated in Fig. 3 showing the two parallel series of dentils or serrations 85 4 for cutting the wood of the pencil and the two parallel series of smaller or finer dentils or serrations 5 for working on the lead of the pencil. This view of the drawing also illustrates the blank central space 90 6 between the two series of serrations 5 and which constitute the smooth inner surface of the rounded fold of the sharpener and serves as an abutment for the end of the lead to prevent further insertion of the 95 pencil after the proper point has been made.

For properly bracing and strengthening the walls of the device, I provide proper connections between said walls at the ends thereof. These connections in the blank 100 illustrated in Fig. 3, include an extension 7 on one wall and an extension 8 on the other wall adapted to be folded, as illustrated in Fig. 1. The extension 7 is formed with a projecting portion 9 adapted to be folded 105 under the opposite wall to support the same; and the extension 7 is provided with an additional projection 10 adapted to be extended over the opposite wall as illustrated in Fig. 1 to permit slight spreading or 110 movement of the walls away from each other to accommodate pencils of different diam-

ters. The extension 8 is formed with a projection 11, corresponding to the projection 9, and with a projection 12 corresponding to the projection 10 and similarly bent or folded to coöperate with the opposite wall. These two connections between the walls of the device prevent compression of the walls and also limit their spreading to permit pencils of different diameters to be passed between the walls to be sharpened.

The extension 8 is formed with a hole 13 adapted to receive the pencil when the device is carried in the pocket. The extension 7 is formed with a smaller hole 14 through which the point of the pencil extends. When the pencil is thus inserted in the device it is protected by the walls between which it is mounted, and the point of the pencil being extended through the hole 14 is protected and will not be broken without considerable violence.

The various corners of the device are preferably rounded off, as shown at 15 in Fig. 2, so that when the device is carried in the pocket it will not cut the cloth.

In using the device the end of the pencil to be sharpened is inserted between the walls 2 and is revolved first in one direction and then in the other, at the same time being pressed into engagement with the serrations 4. The pencil is revolved in opposite directions continuously until the bluntly pointed end of the lead contacts with the smooth wall 6 at the fold. Further cutting or abrasion is then prevented and the pencil is ready for use. The fact that the walls 2 may be slightly separated within the limits permitted by the folded projections on the extensions 7 and 8 permits the insertion and manipulation of hexagonal pencils, or other pencils slightly larger than the usual or standard sizes.

Variations in the construction of the device may be made without departing from the scope of the invention, but I do not restrict myself to the exact features of construction and arrangement illustrated and described.

What I claim and desire to secure by Letters Patent is:—

1. A pencil sharpener, comprising a single integral section of sheet metal having two parallel series of abrading dentils or serrations on one side thereof integral with a smooth surface between said series, said section being folded along said smooth surface to provide two converging walls having the abrading dentils or serrations on their inner surfaces, and having the smooth surface aforesaid forming a smooth connection between said walls permitting movement of said walls toward and away from each other and constituting an abutment for the point of the lead and limiting movement of the pencil toward the converging edges of the walls while the pencil is being sharpened; and means for supporting a pencil between said walls when the sharpener is idle and for limiting movement of said walls away from each other.

2. A pencil sharpener, comprising a section of sheet metal having two parallel series of abrading dentils or serrations on one side thereof and a smooth surface between said series, said section being folded along said smooth surface to provide two converging walls having the abrading dentils or serrations on their inner surfaces and having the smooth surface aforesaid forming a smooth connection between said walls, permitting movement of said walls toward and away from each other and constituting an abutment for the point of the lead and limiting movement of the pencil toward the converging edges of the walls while the pencil is being sharpened, and means for supporting a pencil between said walls when the sharpener is idle and for limiting movement of said walls away from each other.

3. A pencil sharpener, comprising a single integral section of sheet metal having two parallel series of abrading dentils or serrations integral with one side thereof and a smooth surface between said series, said section being folded along said smooth surface to provide two converging walls having the abrading dentils or serrations on their inner surfaces, and having the smooth surface aforesaid forming a smooth connection between said walls permitting movement of said walls toward and away from each other and constituting an abutment for the point of the lead and limiting movement of the pencil toward the converging edges of the walls while the pencil is being sharpened, and means for supporting a pencil between said walls when the sharpener is idle and for limiting movement of said walls away from each other.

4. A pencil sharpener, comprising a single integral section of sheet metal having two parallel series of abrading dentils or serrations integral with one side thereof and a smooth surface between said series, said sections being folded along said smooth surface to provide two converging walls having the abrading dentils or serrations on their inner surfaces, and having the smooth surface aforesaid forming a smooth connection between said walls permitting movement of said walls toward and away from each other and constituting an abutment for the point of the lead and limiting movement of the pencil toward the converging edges of the walls while the pencil is being sharpened, and means for supporting a pencil between said walls when the sharpener is idle and for limiting movement of said walls toward each other when the sharpener is in use.

5. A device of the character described, comprising a section of sheet metal having two parallel series of abrading dentils or serrations for the wood on one side thereof and

- also having two parallel series of finer abrading dentils or serrations for the lead between the serrations for the wood, and having a smooth surface between and separating the finer series of dentils or serrations, said section being folded along said smooth surface to provide two converging walls having the several series of dentils or serrations on their inner surfaces, and having the smooth surface aforesaid forming a smooth connection between said walls at their converging edges constituting an abutment for the point of the lead and limiting movement of the pencil toward the converging edges of said walls while the pencil is being sharpened. 5
6. A device of the character described, comprising a section of sheet metal having two parallel series of abrading dentils or serrations on one side thereof and a smooth surface between said series, said section being folded along said smooth surface to provide two converging walls having the abrading dentils or serrations on their inner surfaces and having the smooth surface aforesaid forming a smooth connection between said walls at their converging edges constituting an abutment for the point of the lead and limiting movement of the pencil toward the converging edges of said walls while the pencil is being sharpened; and two parallel walls extending from said converging walls for guiding the pencil to be sharpened. 25
7. A device of the character described, comprising two parallel walls having smooth inner surfaces for guiding the pencil to be sharpened, two converging integrally united walls in connection with said parallel walls and being capable of movement toward and away from each other, means in connection with said parallel walls for limiting movement of both ends of said walls toward each other when the device is in use and arranged to support a pencil when the device is idle, 40 and abrading teeth or serrations on the inner surfaces of said converging walls.
8. A device of the character described, comprising two parallel walls having smooth inner surfaces for guiding the pencil to be sharpened, two converging integrally united walls in connection with said parallel walls and being capable of movement toward and away from each other, a lateral extension in
- connection with one of said walls, a projection on said extension projecting inwardly over the end of the other wall for limiting movement of said walls away from each other, and abrading teeth or serrations on the inner surfaces of said converging walls. 55
9. A device of the character described, comprising a single section of sheet metal folded to provide two parallel walls and having smooth inner surfaces for guiding the pencil to be sharpened, two converging integrally united walls in connection with said parallel walls and being capable of movement toward and away from each other; means limiting movement of said walls toward each other; means limiting movement of said walls away from each other; and abrading teeth or serrations integral with the inner surfaces of said converging walls. 60
10. A device of the character described, comprising two parallel walls for guiding the pencil to be sharpened, two converging integrally united walls in connection with said parallel walls, and abrading teeth or serrations on the inner surfaces of said converging walls. 75
11. A device of the character described, comprising two parallel walls for guiding the pencil to be sharpened and capable of spreading movement, means limiting the spreading movement of said walls, two converging integrally united walls in connection with said parallel walls, and abrading teeth or serrations on the inner surfaces of said converging walls. 80
12. A device of the character described, comprising two parallel walls capable of spreading movement, means limiting the spreading movement of said walls, two converging integrally united walls in connection with said parallel walls, a series of abrading teeth or serrations for the wood on the inner surface of each of said converging walls, a series of finer serrations for the lead on the inner surfaces of said converging walls near their line of convergence, and a smooth abutment surface for the point of the lead on the inner surface of the converging portion of said converging walls. 95

In witness whereof I have signed this specification.

GEORGE BULLOCK.
